Kaufmann
ATTORNEY

UNITED STATES PATENT OFFICE

ADAM DASCH, OF NEW YORK, N. Y.

ILLUMINATED SIGN

Application filed October 8, 1929. Serial No. 398,150.

This invention relates to curtains or awnings in general and particularly to advertising and illuminating means connected therewith.

5 One object of my invention is to provide in combination with an awning a transparent or translucent fringe, flap or end, adapted to receive advertising matter and further adapted to be illuminated at night.

10 Another object of my invention is to provide in combination with curtains or awnings, a collapsible framework adapted to have an equipment thereon for illuminating such transparent fringe, edge or flap from the rear

15 thereof, while at the same time providing illumination of the pavement or store window or whatever place the awning or curtain protects.

The foregoing and further objects will be 20 more fully apparent from the following description and the accompanying drawings, forming part of my disclosure, but by no means intended to limit me to the actual showing, and in which

25 Figure 1 is a perspective view of a portion of an awning showing my invention.

Figure 2 is a horizontal cross sectional view through a portion of the framework.

Figure 3 is an enlarged cross sectional view 30 through the cross member of the framework, and

Figure 4 is a vertical, longitudinal cross sectional view through a portion of the cross member showing the arrangement of illuminating bulbs.

35 Referring to the drawings, numeral 10 denotes a door or window frame to which is attached a roller 11 forming part of the framework of my device. Below the attachment 40 of the roller there will be seen a hinge 12, from which extends a side member 13 towards the cross member 14. Both frame members 13 and 14 are hollow, as can be clearly seen in Figure 2.

45 Attached to the roller 11 there will be seen

a curtain or awning member 15, preferably made of fabric or any other convenient material, and adapted to be rolled up upon the roller or released therefrom according to desire. The free end of the fabric member 15 is attached to cross member 14. Extending from the fabric member downwardly is a transparent or translucent strip 16 preferably made of noninflammable or fire-resisting material, as for instance, mica, unburnable celluloid, etc. This unburnable fringe is preferably provided with advertising matter and it is disposed on the outer edge of the cross member 14.

50 Referring to Figures 2, 3, and 4 it will be clearly seen that an electric conduit 17 passes through the wall into side member 13 and leads into cross member 14, from which branches extend through apertures 18, provided in member 14, to sockets 19, in which 55 are placed electric bulbs 20. These bulbs are arranged in rear of transparent fringe 16 and are adapted to illuminate the latter.

55 It is obvious that the fringe can be illuminated when the curtain or awning is either 60 in downward or collapsed positions, the fringe having the tendency of hanging vertically downwards from cross member 14.

70 While I have shown a specific structure of my device, be it understood that changes and 75 improvements may be made within the broad scope of my idea, and I therefore reserve for myself the right to make such changes and improvements.

I claim:

75 1. In an illuminated sign, a fabric member, a collapsible framework provided with illuminating means, a roller forming part of said framework and adapted to facilitate the rolling up of said fabric member, and a transparent fringe associated with the free end of the latter for receiving advertising matter and disposed in front of said illuminating means.

80 2. In an illuminated sign, a framework

85

90

comprising a roller and a collapsible frame
adapted to cooperate with said roller and
consisting of hollow side members and a hol-
low front member, the latter provided with a
5 plurality of illuminating means, a fabric
member extending from said roller to said
front member and adapted to be drawn up
by said roller, and a transparent fringe asso-
ciated with the free end of said fabric mem-
ber and disposed in front of said illuminating
10 means.

In testimony whereof I affix my signature.

ADAM DASCH.
